CLAIM

The ornamental design for a gas filling nozzle as shown and described.

DESCRIPTION

FIG. 1 is a front elevational view of the gas filling nozzle of the present invention showing our new design, the rear elevational view being a mirror image of the front elevational view, and the top and bottom views each being identical to the front elevational view;

FIG. 2 is a left-side view thereof;

FIG. 3 is a right-side view thereof; and,

FIG. 4 is a top, front perspective view thereof.
